A. W. LISSAUER -

METHOD OF EVAPORATION

Filed July 29, 1924

UNITED STATES PATENT OFFICE.

ADOLPH W. LISSAUER, OF LOUISVILLE, KENTUCKY, ASSIGNOR TO LOUISVILLE DRYING MACHINERY CO. INC., OF LOUISVILLE, KENTUCKY, A CORPORATION OF KENTUCKY.

METHOD OF EVAPORATION.

Application filed July 29, 1924. Serial No. 728,849.

To all whom it may concern:

Be it known that I, ADOLPH W. LISSAUER, a citizen of the United States, and a resident of the city of Louisville, county of Jefferson, and State of Kentucky, have invented a new Method of Evaporation, of which the following is a full, clear, and exact description.

The invention relates to a method for evaporation, particularly suitable for filtrates of distillers' slop, or the liquor from the sulphite process in paper-making. The method has for its object a more economical way of evaporation. It utilizes the waste flue gases obtained from direct evaporation of the liquor or the flue gases available from any other furnaces.

A distinct feature of this method is that the flue gases act upon a spray of liquor in the absence of the vapor resulting from direct evaporation of the liquor.

Another object of the invention is to provide a method which can be carried out with an equipment of low cost and upkeep.

The appended drawing illustrates a form of apparatus suitable for my method of evaporation and in which—

Figure 1 is a vertical section on line 1—1, Figure 2, and

Figure 2 is a longitudinal section on line 2—2, Figure 1.

Referring to the drawing, 3 is the direct-fired evaporator for heating of the raw liquor and where the greater part of evaporation is done. This direct-fired evaporator is in effect nothing but a horizontal tubular fire tube boiler, in which the level of the liquor is kept just above the top row of tubes by a suitable float 4 that controls the inflow of the liquor from the tube 5. The boiler is set in brick work 6 and the flue gases from the burning of the fuel in the furnace 7, pass around the shell, then through the tubes 8 into the front housing 9 of the boiler.

The flue gases are drawn from the front housing 9 by a fan 10 which forces the flue gases through a spray evaporator 11. The fan 10 will be of the cinder-separating type when dry fuel is used for direct evaporation, by which I mean evaporation produced by the heat of combustion.

The spray evaporator has a plurality of rotary discs 12 against which the liquor is forced through nozzles 13 to which the

liquor is supplied by a pump 14 that draws the liquor from the bottom of the boiler. The spray discs 12 are rotated by means of a suitable transmission mechanism 14' provided in the spray evaporator. 60

The spray evaporator is provided with eliminators 15 near the flue gases outlet 16. The said eliminators cause the flue gases passing to the outlet 16 to deposit whatever dust there is in them on the eliminators and from which the dust is washed down by the liquor which is also deposited by the outgoing flue gases. 65

The sump in the spray evaporator is divided into two parts, 17 and 18, by a partition 19 located in proximity of the eliminators. This partition 19 has a wier which permits the overflow from compartment 17 to compartment 18. The spray nozzles 13 are located over the compartment 18 while the eliminators are located above the compartment 17. The sediment which is washed off the eliminators deposits in compartment 17 and is drawn off intermittently through a pipe 20. The said compartment 17 has also a draw-off pipe 21 for concentrated liquor. The liquor in the compartment 18 overflows through a pipe 22 into the boiler 3, so that the pump 14 continuously circulates the liquor that is being concentrated. 75 80 85

To prevent loss by radiation the spray evaporator 11 is surrounded by a jacket 23 which has a vapor stack 24 forming an outlet for the vapor, which is supplied to the jacket from the boiler 3 through a series of outlets 25. Through these outlets the overflow pipes enter the boiler. 90

Although I show a spray evaporator coupled to the direct-fired evaporator, that is using the flue gases of the direct-fired evaporator for further evaporation in the spray evaporator, the spray evaporator may be used in conjunction with any other supply of flue gases, in which case the recirculating pump will simply draw the liquor 100 to be sprayed into a current of the flue gases from the sump. In such case it is self evident that the greater part of the concentration has been done previously to the introduction of the liquor to the sump of the 105 spray evaporator.

From the above description of my method it will be seen that where the flue gases come in contact with the spray evaporator, no vapors are present from direct evapo- 110

tion of the liquor, thereby I am able to utilize the heat of the flue gases to its full extent, for the purpose of evaporation or concentration.

5. I claim:

1. In a method of evaporation or concentration, steps which consist in bringing liquor into heat exchange with products of combustion, and atomizing the said liquor into a current of flue gases free of vapors from said liquor.

2. In a method of evaporation or concentration, steps which consist in bringing a liquor into heat exchange with products of combustion, forming a current of flue gases free of vapors from said liquor, spraying into the said current said liquor, and jacketing said current of flue gases and spray with vapors from the liquor.

3. In a method of evaporation or concentration, steps which consist in bringing a liquor into heat exchange with products of combustion so that the products of evaporation from the liquor do not mix with the products of combustion, forming a current of flue gases resulting from combustion and free of vapors from the liquor, and spraying into the said current of flue gases the said liquor.

4. In a method of evaporation or concentration, steps which consist in atomizing a liquor into a current of flue gases free of vapor from said liquor and while said liquor is in heat exchange with products of combustion from which the flue gases are derived.

ADOLPH W. LISSAUER.
